UNITED STATES PATENT OFFICE.

CARL S. SWANSON, OF NEW YORK, N. Y.

SPARK PLUG.

Application filed November 11, 1922. Serial No. 600,375.

To all whom it may concern:

Be it known that I, CARL S. SWANSON, a subject of the King of Sweden, and a resident of the city of New York, borough of

5 Manhattan, in the county of New York and State of New York, have invented a new and Improved Spark Plug, of which the following is a full, clear, and exact description.

10 This invention relates to improvements in spark plugs for internal combustion engines, the object of the invention being to provide a spark plug having a plurality of spark gaps so arranged and related and "spark-insulated," to coin a term, that a plurality of the sparks will absolutely always be produced at each closing of the circuit by the timer of the like forming a part of the ignition system of the engine.

20 Another object of the invention is to provide a spark plug as just indicated, which will not be unduly expensive to manufacture, and which, most importantly, will strengthen rather than weaken the total

25 sparking efficiency of the plug, by a true intensifying rather than an enfeebling of the individual sparks, and at the same time prevent any possibility of short circuiting parts of various electrode elements provided

30 for establishing the various sets or pairs of

of sparking points.

It has heretofore been proposed to provide a plurality of gaps between a plurality of electrode elements at the sparking or inner end of a spark plug. It has also heretofore been proposed to provide a plurality of such gaps in the presence of at least one of such electrode elements constituted as a rod-like or reduced projection from the

40 metallic jacket of the plug, commonly called the ground electrode.

Again, it has heretofore been proposed to provide a plurality of sparking points at the sparking or inner end of a spark plug, and in combination therewith to provide spark-baffles or insulating members or projections for spark-insulating various dissimilar pluralities of sparking points. Other investigators have gone even farther, and have

50 provided insulating interponents serving to segregate or hold to one single sparking group each of several pairs of sparking points. It has heretofore also been proposed partially to embed in the central core of insulation a plurality of spiral coils of conducting material having a protruding coil

terminus or a plurality of protruding coil termini to act as one or both of a pair of sparking points, and likewise partially to embed in such core cotter-pin-shaped conductors with the eye of each pin uppermost and embedded in the core; to provide a plurality of what may be termed "floating" electrode elements.

I have discovered that remarkably efficient results are obtained, when a sparking point of each of two gaps is carried at the end of a reversely bent "floating" conductor shaped substantially like an ordinary hairpin, that is to say, an electrode member of substantially U-shape and inverted and embedded in the insulating core all over except at the lower terminal portions of the legs of the U, these legs protruding below such core but located completely on opposite sides of a plane depending rib or wall of insulation at the bottom of the core, such wall or rib lying in a plane substantially perpendicular to the plane of the U-shaped floating electrode. It is quite important, I have found, that but one such floating electrode be used. Further, I have found that this discovery, to be carried out with best results, must be carried out in the presence of a proper design of the members, and particularly as to the total number of spark gaps employed and the size of each such gap. It is especially important that the individual gaps do not exceed a certain permissible maximum; and likewise as to the number of gaps employed.

In the accompanying drawing, wherein a preferred embodiment of the invention according to the above discoveries is illustratively shown.

Fig. 1 is a central axial section;

Fig. 2 is a side elevation, partially broken away and partially in section, looking toward the left in Fig. 1;

Fig. 3 is a side elevation of the insulation core of Figs. 1 and 2, viewed as in Fig. 2; and

Fig. 4 is a perspective view of the core and embedded parts with a portion of the former broken away at the top.

Similar reference characters refer to similar parts in the several views.

It will be seen that the spark plug illustrated includes the usual metallic jacket 5 and male nut 6, clamping in place the insulating core 7 securely and in a compression-proof manner by means of the inter-

posed gaskets 8. At its protruding top the core carries a binding post 9 relative to the upper end of a center electrode 10. The parts as so far described are of course 5 merely illustrative of a conventional spark plug design.

It will be noted, however, that said center electrode diverges downwardly sufficiently 10 away from the center line of the core to project below the lower end of the stem to one side of a diametral line across the core bottom; and that said core carries integrally a dependent diametral plane wall or rib 11. This rib or wall, it will be noted, is shaped 15 in side elevation like a truncated triangle, with the base uppermost.

Said electrode 10 provides a sparking point 10^a on one side of wall 11.

The single floating electrode employed 20 pursuant to my discovery above discussed is indicated at 12, and it will be seen that the same has its upper reversely bent end and the major part of its hairpin-formation embedded in the core 9 and wholly insulated 25 from any part of center electrode 10. The lower terminal portions of electrode 12 depend below the bottom of main portion of core 7, one on each side of wall 11, to establish the sparking points 12^a and 12^b, especially 30 good results being obtained when the former point is located as the terminus of a horizontally bent length 13, as shown in Fig. 1; establishing a first spark gap at the pair of points 10^a and 12^a.

The only other electrode member of the 35 new combination is the ground electrode 14, establishing a sparking point 14^a, and so establishing a second spark gap at the pair of points 14^a and 12^b.

It will be noted that the spark gaps at 40 10^a—12^a, and at 12^b—14^a are each not greater, substantially, than the thickness of each electrode element; and that only two 45 gaps are provided, as I have found that an increase beyond these limits results in enfeeblement rather than intensification of the total sparking or ignition efficiency of the plug, when each pair of sparking points or 50 spark gaps is segregated from another by an insulating baffle such as indicated at 11, and when the electrode 12 is shaped as described and of an ohmic characteristic such as that indicated in the drawing where the 55 material of the electrode is ordinary electrode metal.

Various slight changes might be made in the general form and arrangement of the parts described without departing from the

invention, and hence I do not limit myself to the precise details set forth, but consider myself at liberty to make such changes and alterations as fairly fall within the spirit and scope of the appended claims.

I claim:

1. In a spark plug having a jacket, a core 65 of insulating material, and a center electrode partially embedded in said core, the combination of a single dependent, reduced insulating baffle at the lower end of the core, and a single substantially U-shaped floating electrode element having the free termini of the legs thereof protruded below the bottom of the core with one located on one side of said baffle and one on the other; said baffle being a plane wall arranged substantially diametrically across the bottom of the core and said center electrode is a substantially straight rod arranged eccentrically of the core axis.

2. In a spark plug having a jacket, a core 70 of insulating material, and a center electrode partially embedded in said core, the combination of a single dependent, reduced insulating baffle at the lower end of the core, and a single substantially U-shaped floating electrode element having the free termini of the legs thereof protruded below the bottom of the core with one located on one side of said baffle and one on the other; said baffle being a plane wall arranged substantially 75 diametrically across the bottom of the core and defining substantially a truncated triangle in side elevation, with the base of the triangle uppermost.

3. In a spark plug having a jacket, a core 80 of insulating material, and a center electrode partially embedded in said core, the combination of a single dependent, reduced insulating baffle at the lower end of the core, and a single substantially U-shaped floating electrode element having the free termini of the legs thereof protruded below the bottom of the core with one located on one side of said baffle and one on the other; said baffle being a plane wall arranged substantially 85 diametrically across the bottom of the core and defining substantially a truncated triangle in side elevation, with the base of the triangle uppermost.

90

3. In a spark plug having a jacket, a core 95 of insulating material, and a center electrode partially embedded in said core, the combination of a single dependent, reduced insulating baffle at the lower end of the core, and a single substantially U-shaped floating electrode element having the free termini of the legs thereof protruded below the bottom of the core with one located on one side of said baffle and one on the other; a ground 100 electrode being provided having a terminal point adjacent to the terminal point of one of the legs of said floating electrode, the terminal point of the other leg of said floating electrode being adjacent to the lower 105 terminal point of the central electrode, said electrodes all being of the same material and of circular cross-section and of the same 110 cross-sectional area, and the gap at each pair of electrode termini being substantially equal to the diameter of said area.

CARL S. SWANSON.
